UNITED STATES PATENT OFFICE

HJALMAR C. JERNBERG, OF CHICAGO, ILLINOIS

WASTE BASKET

Application filed February 11, 1930. Serial No. 427,569.

This invention relates to a waste basket and has for its prime object the provision of a structure which may be incorporated in a desk in a convenient manner for use.

Another very important object of the invention resides in the provision of a waste basket structure of this nature which is simple, easy to attach in place, strong and durable, inexpensive to manufacture, thoroughly efficient and reliable in use.

With the above and numerous other objects in view as will appear as the description proceeds, the invention resides in certain novel features of construction, and in the combination and arrangement of parts as will be hereinafter more fully described and claimed.

In the drawing:

Figure 1 is a vertical section through a desk showing my improved waste basket in place,

Figure 2 is a front elevation thereof,

Figure 3 is a vertical section through the waste basket structure,

Figure 4 is a top plan view thereof,

Figure 5 is a sectional view taken substantially on the line 5—5 of Figure 3,

Figure 6 is a detail sectional view of the inlet end of the waste basket showing a modification with a door,

Figure 7 is a top plan view of another embodiment of the invention.

Referring to the drawing in detail it will be seen that the numeral 5 denotes a desk of conventional construction. My improved waste basket comprises a vertical hollow receptacle 6 having an opening at the bottom of the front wall as is shown at 7 through which is slidable a drawer 8. This receptacle 6 merges into a laterally extending outwardly tapering portion 9 terminating in a horizontal neck 10.

A plurality of apertured ears 11 are provided on one side of this waste basket so that it may be anchored to the inner side of the desk 5 as is clearly shown in Figures 1 and 2 by suitable fastening means. It will be seen that the inlet neck 10 terminates at the front end of the desk as to be conveniently located for inserting waste paper and

the like therein and the incline of the extension 7 will allow this waste paper and the like to slide down into the receptacle 6 to be deposited into the drawer 8 which may be emptied when necessary or desirable.

In Figure 6 it will be seen that I have shown a slightly modified form of the neck denoted by the numeral 10' and at the entrance of said neck is a hingedly mounted door 12 with which is preferably associated suitable locking means 14.

In Figure 7 I have shown another embodiment of the invention wherein the extension 9' tapers in its width outwardly so that the neck 10a is slightly spaced from the inner side of the desk and therefore arms 15 are extended laterally therefrom terminating in ears 11' which may be anchored to the inner side of the desk.

It is thought that the construction, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In combination with a desk, a waste basket anchored to the inner side of the desk including a vertically disposed receptacle having a forwardly and upwardly inclined extension terminating in a horizontal neck adjacent the front of the desk.

2. In combination with a desk, a waste basket anchored to the inner side of the desk including a vertically disposed receptacle having a forwardly and upwardly inclined extension terminating in a horizontal neck adjacent the front of the desk, the

bottom of the front wall of the receptacle being formed with an opening, and a drawer slidable in said opening.

3. In combination with a desk, a waste basket anchored to the inner side of the desk including a vertically disposed receptacle having a forwardly and upwardly inclined extension terminating in a horizontal neck adjacent the front of the desk, the bottom of the front wall of the receptacle being formed with an opening, and a drawer slidable in said opening, a door hingedly mounted in the end of the neck.

4. A waste basket structure of the class described comprising a vertically disposed receptacle merging at its upper end to a hollow forwardly and upwardly inclined extension terminating in a horizontal inlet neck, and ears on the receptacle at one side for anchoring the same to the inner side of a desk.

5. A waste basket structure of the class described comprising a vertically disposed receptacle merging at its upper end to a hollow forwardly and upwardly inclined extension terminating in a horizontal inlet neck, and ears on the receptacle at one side for anchoring the same to the inner side of a desk, the front wall of the receptacle being provided with an opening and with a drawer slidable in the opening.

6. A waste basket structure of the class described comprising a vertically disposed receptacle merging at its upper end to a hollow forwardly and upwardly inclined extension terminating in a horizontal inlet neck, and ears on the receptacle at one side for anchoring the same to the inner side of a desk, the front wall of the receptacle being provided with an opening and with a drawer slidable in the opening, said extension tapering forwardly.

In testimony whereof I affix my signature.

45 HJALMAR C. JERNBERG.
